PRINTING MACHINE

Harry L. Latz, New York, N. Y., and Stephen H. Plum, 2d, Madison, N. J., assignors to Harry Latz Service Inc., New York, N. Y., a corporation of New York

Application January 4, 1936, Serial No. 57,464

20 Claims. (Cl. 101—57)

The invention relates to printing machines and has for its object to provide a simple machine adapted to automatically print individual and separate items, as exemplified by the names of 5 different persons, in predetermined succession or other sequence in an efficient manner. The invention contemplates primarily the provision of a novel machine whereby printed impressions of predetermined character may be added to matter previously printed or otherwise produced, so as to harmonize therewith and to give each completed sheet or its equivalent an individual appearance or a personal character. Other more specific objects will appear from the description 10 hereinafter and the features of novelty will be pointed out in the claims.

In the accompanying drawings which illustrate an example of the invention without defining its limits, Fig. 1 is a side elevation of 20 the novel machine; Fig. 2 is a similar view from the opposite side; Fig. 3 is a sectional elevation approximately through the longitudinal center of the machine; Fig. 4 is a horizontal section on the line 4—4 of Fig. 3; Fig. 5 is an 25 end elevation; Fig. 6 is a vertical cross-section on the line 6—6 of Fig. 3; Fig. 7 is a fragmentary vertical section on the line 7—7 of Fig. 5; Figs. 8, 9, and 10 are detail sections showing parts of the machine in different positions; Fig. 11 is an 30 enlarged detail section on the line 11—11 of Fig. 9; Fig. 12 is a fragmentary plan view of the linking mechanism; Fig. 13 is a fragmentary section on the line 13—13 of Fig. 12; Fig. 14 is an enlarged fragmentary section on the line 14—14 of Fig. 35 13, and Fig. 15 is a detail section on the line 15—15 of Fig. 7.

In its illustrated form the machine includes a frame consisting of spaced, parallel upright side members 15 and a base-plate 16 extending between and connecting said side members 15, the latter in addition serving as supports for a horizontal bed-plate 17 located at a distance above the base plate 16 as shown in Figs. 3, 5, and 6. The side members 15 of the frame are continued 40 in the form of horizontal supports or arms 18 which project in spaced parallel relation over the bed-plate 17 and have their free ends connected by means of a transverse guide plate 19 removably secured in position in any suitable 45 manner as by means of bolts 20.

As shown in Fig. 15 the guide plate 19 is recessed on its inner face for the accommodation of an upper carrier 21 which is maintained in place by means of guide strips 19a removably secured in 50 position in any convenient manner as by bolts

19b; the upper carrier 21 at its lower end is provided with a stamping or pressure member 22 of any suitable type and fixed in place in any conventional way, the arrangement being such that said upper carrier 21 is vertically slidable in 5 the recess of said guide plate 19. For the purpose of vertically reciprocating the upper carrier 21 and stamping or pressure member 22, in the operation of the machine, said carrier is supported upon a head 23, preferably so as to be 10 vertically adjustable relatively thereto, the head 23 fitting into a recess with which the upper carrier 21 is provided as illustrated in Fig. 15. The adjustment of the upper carrier 21 on the head 23 may be effected in any suitable manner; in the 15 illustrated example, the carrier 21 for this purpose is provided with a lug 24 in which an adjusting screw 25 is rotatably mounted, and with a second lug 26 provided with a recess for the accommodation of a bearing projection 27 located at the 20 lower end of said screw 25 as shown in Figs. 3 and 7, a hand wheel 28 or equivalent device being provided on said screw 25 to facilitate the manipulation thereof. The aforesaid screw 25 passes through and is in threaded engagement with the 25 head 23 so that an operation of said screw 25 will slidably adjust the carrier 21 on said head 23 in vertical directions; as shown in Fig. 15 set screws 29 or any equivalent suitable means 30 may be provided for fixing the upper carrier 21 in an adjusted position on the head 23.

In the illustrated example, the head 23 and the upper carrier 21 and stamping or pressure member 22 are vertically reciprocated in synchronism with the associated elements of the machine by 35 means of a rocking lever 30 pivoted at 31 and having its one end pivotally connected at 32 with said head 23 as shown in Figs. 3, 7, and 15; for the purpose of illustrating an example of the means for rocking the lever 30 on its pivot 31, the 40 other end of said lever 30 carries a roller 33 projecting into a cam groove 34 of a cam disk 35 fixed upon a shaft 36 suitably journaled in the arms 18. In order to permit the upper carrier 45 21 and its associated elements to reciprocate in a straight vertical path in the recessed guide plate 19 without jamming as a result of the rocking of the lever 30 in an arc, the pivot 31 is carried by a frame 37 which depends from a pivot 38 mounted on the arms 18 as shown in Figs. 3 and 6. 50 Under certain conditions it may be desirable to vary the vertical movements of the stamping or pressure member 22 for the purpose for instance of adjusting the effective pressure developed thereby; the illustrated example accordingly 55

shows the pivot 38 in the form of a shaft journalled in the arms 18 and provided with eccentrics 39 located within circular bearing rings 40 with which the frame 37 in such case is provided. As 5 illustrated in Fig. 3, the means for actuating the eccentrics 39 may consist of an operating lever 41 pivoted at 42 on an arm 18 and connected by means of a link 43 with a lug 44 which is fixed upon and projects radially from the pivot shaft 10 38.

As shown in Fig. 3, the bed-plate 17 is provided with an opening 45 beneath and in registry with the stamping or pressing member 22, the latter being located in vertical registry with a 15 lower carrier 46 adapted to reciprocate in opposed relation to the upper carrier 21 as shown in Fig. 3. The lower carrier 46 is vertically slidable in stationary upright guideways 41 forming part of a 20 guide plate 48 suitably secured between the side members 15, and is vertically reciprocable in said guideways 41 in properly timed relation with the upper carrier 21 and its associated elements by 25 means of any suitable mechanism. In the illustrated example the latter consists of a rocking lever 49 carried by a shaft 50 rotatably mounted on the side members 15 and having its one end forked at 51 for slidable engagement with a bearing block 52 fixed upon a pivot pin 53 journalled between lugs 54 forming part of or secured to the 30 lower carrier 46 as shown in Figs. 3 and 7. The opposite end of the lever 49 carries a roller 55 which projects into the cam groove 56 of a cam disk 57 mounted to rotate with a shaft 58 journalled on the side members 15 in any convenient 35 manner.

The novel machine is designed to operate with printing or impression slugs 59 which carry the individual items to be printed, as exemplified by the names of different persons, in the form of 40 type cast upon the upper faces of said slugs in any customary way; the slugs 59 are fed to the lower carrier 46 and removed therefrom in succession in a manner to be more fully described hereinafter. For the purpose of removably accommodating the 45 successive slugs 59 the lower carrier 46 is provided with a gripping means automatically controlled to provide the desired results. As shown in the drawings the aforesaid gripping means consists of a plate or stop 60 fixed upon the lower carrier 50 46 and projecting above the upper face thereof as illustrated in Figs. 3 and 7; for co-operation with the plate or stop 60 the lower carrier 46 is further provided with a movable clamping member 61 located in spaced opposed relation to said plate 55 60 and carried by a member 62 pivoted at 63 between the lugs 54 of said carrier 46 as shown in Fig. 7. The member 62 carries a pin 64 which projects slidably through the lower carrier 46 and supports a coil spring 65 located between the carrier 46 and an adjustable abutment exemplified by the nuts 66 threaded upon said pin 64 as shown in Figs. 3 and 7; the spring 65 by acting 60 on the nuts 66 or their equivalent serves to force the clamping member 61 into engagement with 65 the successive slugs 59 for clamping the same against the plate or stop 60 during the printing operations. The successive slugs 59 may be released at the proper time for removal from the lower carrier 46 in any convenient manner, as 70 for instance by locating a wedge-shaped cam 67 upon the member 62 which is provided with an opening 68 for the accommodation of said cam 67 as illustrated in Fig. 7. The cam 67 is arranged to co-operate with a releasing device 75 illustrated in the form of a rod 69 slidably mount-

ed in the lower carrier 46 for vertical movement relatively thereto; the rod 69 has its lower end resting upon the base plate 16 and is of sufficient length to extend into operative engagement with the cam 67 in the opening 68 when the carrier 5 46 is in its lower position as shown in Fig. 7. With the arrangement set forth the rod 69 will be retained upon or dropped back upon the base plate 16 by gravity as the carrier 46 is raised, and when said carrier 46 is lowered will engage the 10 cam 67 and thereby pivotally actuate the member 62 and clamping member 61 against the tension of the spring 65 to release one slug 59 for removal from the carrier 46 and to permit a successive slug 59 to be positioned thereon. In 15 order to relieve the mechanism whereby the lower carrier 46 is reciprocated, from excessive strains during the successive printing operations, the machine is provided with means whereby said carrier 46 is supported from below during each 20 printing stage. In the illustrated example the aforesaid supporting means is exemplified by an arm 70 fixed upon a pivot shaft 71 journalled in the side members 15 and provided with a shoulder 72 arranged to extend beneath the lower carrier 25 46 when the latter is in its raised position, said arm 70 having its upper end movable in an opening 73 in the guide plate 48 as shown in Fig. 7. A spring 74 connected with a lug 75 of the arm 70 and with a fixed pin 76 or its equivalent tends 30 to pivotally swing the upper end of the arm 70 toward the carrier 46. The arm 70 may be automatically operated in any suitable manner to remove the shoulder 72 from beneath the raised carrier 46 at the proper time, as for instance by 35 means of a link 77 pivotally connected at 78 with the aforesaid lug 75 and at 79 with a lug 80 fixed upon a pivot pin 81 which also carries a tripping pawl 82 and is rotatably mounted in a bearing 83 upon the base plate 16; the tripping pawl 82 40 projects into the path of a projection 84 carried for instance by a cam disk 85 fixed upon the shaft 58 as shown in Fig. 3.

The machine further includes a container for a supply of slugs 59, said container being illustrated in the form of a horizontal chute 86 extending lengthwise of the one side member 15, as shown in Fig. 4, and dimensioned transversely in accordance with the length of the slugs 59 which said chute 86 is designed to accommodate. The 50 chute 86 is suitably supported in the machine and terminates at its delivery end in registry with transferring means and adjacent to an opening 87 formed in the aforesaid side member 15, as illustrated in Figs. 1 and 4. In the example 55 shown in the drawings, a guide member 88 is located in transverse relation to the delivery end of the chute 86 and is provided with an upright guide wall 89 which extends into delivery relation to the lower carrier 46, as shown in Fig. 4, 60 said guide member 88 and guide wall 89 serving to guide and maintain the transferring device of the aforesaid transferring means in its intended operative path.

Because of the fact that the items to be 65 printed, such as the names of individuals, vary in length and that accordingly the individual lines of type located on the slugs 59 are of different length in different slugs 59, it is desirable to provide a transfer device which will compensate for such differences, in order that the slugs 59 may all be automatically transferred to the printing mechanism in such a way that the lines of type on said slugs will be centered in the proper printing position regardless of any dif- 70 75 75

ferences in the length of said lines of type; the illustrations in Figs. 8, 9, and 10 diagrammatically show lines of type *a* and *b* of different lengths on two individual slugs 59. It is to be understood that the expression "lines of type" is used herein in a broad sense and intended to include any impression producing means suitable to the purposes for which the machine may be used.

10 For the above reasons the transfer device accordingly may consist of a transfer member 90 of generally rectangular shape in cross-section and including two parallel side walls *c* spaced apart as shown in Fig. 11. The side walls *c* are preferably provided with guide grooves 91 in which propelling or shifting members 92 and 93 are slidably mounted for movement lengthwise of the transfer member 90. The propelling members 92 and 93 are each provided on their opposed faces 20 with racks 94 which slidably fit the space between the side walls *c* and mesh with a pinion 95 journalled in said side walls *c* in the aforesaid space as illustrated in Fig. 11. With the arrangement set forth the propelling members 92 25 and 93 are caused to move lengthwise of the transfer member 90 in inverse relation by the action of the pinion 95 as will appear more fully hereinafter. To facilitate the operation of the propelling or shifting members 92 and 93 in the desired manner, a spring 96 has its one end connected to a lug 97 on the member 92 and its other end attached to a pin or the like 98 fixed to the one side wall *c* as shown in Figs. 8, 9, and 10; the spring 96 exerts a tension tending to draw 30 the propelling or shifting member 92 into the transfer member 90 and consequently, through the medium of the racks 94 and pinion 95, to move the propelling or shifting member 93 out of said member 90.

40 Any conventional mechanism may be provided for shifting the transfer member 90 and its associated elements lengthwise of the guide member 88 and guide wall 89 in transverse relation to the chute 86 for the purpose of transferring successive slugs 59 from said chute 86 to a printing position on the lower carrier 46 as will be more fully described hereinafter. In the illustrated example the aforesaid mechanism comprises a lever 99 pivoted at 100 upon a bracket 101 suitably mounted upon the one side wall 15, said lever 99 being pivotally connected at 102 with a link 103 which in turn is pivotally connected with a pin 104 depending from the transfer member 90 as shown in Figs. 8, 9, and 10; to permit the necessary movements of the pin 104 the guide member 88 is provided with a slot 105 extending lengthwise thereof as also illustrated in Figs. 8, 9, and 10. The lever 99 is oscillated on its pivot 100 in a manner to reciprocate the transfer member 90 in its operative path, by means of a cam 106 fixed upon the shaft 58 and including a cam groove 107 for the accommodation of a roller 108 rotatably mounted upon an arm 109 carried by the lever 99 as shown by dotted lines in Fig. 4.

65 In addition the parts so far described, the machine includes intermittently actuated means for advancing the supply of slugs 59 in the chute 86 in successive steps in a manner to bring successive forward terminal slugs 59 into operative relation to the transfer means to permit said slugs 59 to be individually shifted from said chute 86 to a printing position on the lower carrier 46.

70 As shown by way of example in the drawings, the aforesaid intermittently actuated means in-

cludes an advancing member 110 projecting transversely across the chute 86 and arranged to engage the rearward terminal slug 59 of the supply contained in said chute 86 as shown in Fig. 4. Any suitable mechanism may be provided for 5 intermittently advancing the member 110 in a manner to effect the intermittent advance of the slugs 59. For instance as disclosed in the illustrated example of the machine the mechanism referred to may include a support 111 on which a 10 shaft 112 is suitably journalled, said shaft 112 serving as a pivotal support for the advancing member 110 which is conveniently fixed on said shaft 112 to rock therewith. The support 111 further has a second shaft 113 rotatably mounted 15 thereon and carrying a pinion 114 which meshes with a pinion 115 located on the shaft 112, whereby said two shafts 112 and 113 are geared together as illustrated in Fig. 4; the shaft 113 is provided with a crank handle 116 or equivalent device for 20 rocking the same for the purpose to be more clearly described hereinafter. The support 111 is slidable lengthwise of a grooved guide rail 117 and projects over and is adjustable lengthwise of a rack 118, which itself is slidable lengthwise of 25 a grooved guide rail 119; the guide rails 117 and 119 are located in spaced parallel relation to each other as shown in Fig. 4 and are supported in the machine in contiguous lengthwise relation of the chute 86 in any convenient manner. 30 The advancing member 110 carries a pawl 120 adapted to co-operate with the rack 118 for adjustably connecting said member 110 and its support 111 therewith. The rack 118 is arranged to be slidably advanced in successive steps lengthwise of the guide rail 119 to correspondingly advance the support 111 with the member 110 and the supply of slugs 59 located in the chute 86, and for this purpose is provided with a depending lug 121 which projects downwardly through a slot 40 122 in the guide rail 119 as shown in Fig. 1. The lug 121 is connected by means of a spring 123 with a bracket 124 slidably mounted in a slot 125 of a stationary plate 126, said bracket 124 being carried by an operating member 127; the latter 45 is provided with slots 128 for the accommodation of pins 129 or their equivalent whereby said operating member 127 is slidably supported upon the one side member 15 as illustrated in Fig. 1. The operating member 127 is actuated in one direction 50 in an operative movement by means of a cam projection 130 on the peripheral surface of the cam 106, which co-operates with a roller 131 journalled upon said operating member 127 at one end thereof as shown in Fig. 1; a second 55 spring 132 has its one end attached to the lug 121 and its other end to a fixed pin 133 projecting downwardly from the guide rail 119, and acts in opposition to the spring 123 for the purpose of moving the rack 118 in a return direction relatively to the support 111 and the advancing member 110 carried thereby. In other words, the arrangement is such that in its operative movement the rack 118 acts on the pawl 120 to advance the support 111 and member 110 one step to thereby shift a forward terminal slug 59 into position for transfer from the chute 86 to the printing position on the lower carrier 46; on the other hand during the movement of recovery of said 60 rack 118 under the influence of the second spring 132 the pawl 120 simply rides over the teeth of the rack 118 to a new position thereon, the support 111 and advancing member 110 remaining stationary during this stage ready to be subse- 65

quently advanced another step when the cam projection 130 again acts on the roller 131.

After the printing operation has been effected by a given slug 59 the latter is removed from the printing position on the lower carrier 46 by the next successive slug 59 as it is shifted into printing position on said carrier 46.

For the purpose of disposing of the slugs 59 in an orderly manner as said slugs are removed from the lower carrier 46 the machine is provided with an inclined chute 134 in adjustable receiving relation to the lower carrier 46 and in delivery communication with an inclined trough 135 or its equivalent; as shown in Figs. 2, 4, 5, and 6 the chute 134 and trough 135 are supported upon brackets 136 suitably secured to the one side member 15. As the slugs 59 are successively deposited in the trough 135 said slugs are progressively shifted lengthwise thereof for removal therefrom at will in any convenient manner. In the illustrated example of the machine this shifting of the slugs 59 is accomplished by means of a pushing member 137 normally located at one end of the trough 135 in operative relation to the chute 134 as shown in Figs. 4 and 5. The pushing member 137 is carried by a rod 138 and arm 139 fixed upon a second rod 140 slidably mounted in a bearing 141 forming part of one of the brackets 136, said rod 140 projecting from a supporting member 142 as shown in Figs. 2 and 4; a link 143 has its one end pivotally connected at 144 with the member 142 and its other end pivotally secured at 145 to a disk 146 fixed upon the shaft 58 as illustrated in Figs. 2 and 4.

The machine further includes means for inking the type located on the slug 59 which is in printing position on the lower carrier 46, said inking means being of any suitable type and operating in properly timed relation with the other elements of said machine. In its illustrated form the inking means comprises a frame 147 mounted on rollers 148 adapted to travel lengthwise of guide rails 149 located in opposed parallel relation and fixed upon the inner faces of the side members 15 as shown in Figs. 3, 6, 12, 13, and 14. Inking rolls 150 and 151 are rotatably supported upon the frame 147 by being journaled in the side members thereof, while a third roller 152 is mounted on said frame in a specific manner to be more fully described hereinafter. The inking rolls 150 and 151 are continuously in rolling engagement with actuating rolls 153 while the inking roll 152, in its operative position, is also in rolling contact with one of said actuating rolls 153 as illustrated in Fig. 13. The actuating rolls 153 are carried by shafts 154 which are rotatably mounted in upwardly open recesses 155 formed in the side members of the frame 147, so as to be readily removable therefrom at will. The shafts 154 of the actuating rolls 153 carry pinions 156 which mesh with stationary racks 157 secured to plates 158 projecting laterally from and fixed upon the guide rails 149 as shown in Fig. 14. With this arrangement, as the frame 147 is propelled lengthwise of the guide rails 149, the pinions 156 will roll along and be rotated by the racks 157 to correspondingly rotate the actuating rolls 153; as a result the latter because of their frictional surface engagement with the inking rolls 150, 151, and 152, will cause said inking rolls to be rotated upon their several axes to thereby bring about an efficient inking of said rolls 150, 151, and 152 and an efficient distribution of the ink thereby upon the type of the slug 59 clamped upon the lower carrier 46 at the

time. Ink is supplied to the surface of the roll 152 by means of a transfer roll 159 when the frame 147 is in the retracted position illustrated in Fig. 3, said transfer roll 159 being removably journaled in bearing brackets 160 and arranged to receive a surface coating of ink from a distributing roll 161 removably journaled in an ink reservoir 162 supported upon an auxiliary bed plate 163 extending between and suitably secured to the side members 15 as shown in Figs. 3 and 10. To regulate and control the coating of ink picked up by the distributing roll 161 from the supply in the reservoir 162, a doctor or scraper 164 may be mounted in the reservoir 162 in tangential surface engagement with the roll 161 as illustrated in dotted lines in Fig. 3; the doctor or scraper 164 may be controlled by an adjusting screw 165 for the purpose of adjusting the active edge of said doctor 164 relatively to the surface of the roll 161. It will be understood that in the operation of the inking means, the ink is distributed by the roll 161 to the transfer roll 159 and by the latter to the inking roll 152 each time the latter contacts with said roll 159 in the retracted position of the frame 147; the inking rolls 150 and 151 in turn receive coatings of ink through the medium of the actuating rolls 153 as will be apparent.

The distributing roll 161 is rotated in the reservoir 162 by means of bevel pinions 166 and 30 associated gears which are intermittently actuated by a suitable pawl and ratchet mechanism operated by a slide 167 carrying a roller 168 acted on by a cam 169 secured upon the shaft 58; a spring 170 is effective on the slide 167 to maintain the roller 168 in operative engagement with the cam 169. To still further insure an efficient and uniform inking of the slug 59 which is temporarily clamped upon the lower carrier 46, the inking rolls 150, 151, and 152, during the reciprocation of the frame 147, pass over the inked surface of an inking platen 171 in rolling contact therewith. The platen 171 is rotatably mounted in an upright bearing 172 projecting upwardly from the auxiliary bed plate 163 and 45 is intermittently rotated by a train of gearing 173 operated by suitable pawl and ratchet mechanism controlled by the aforesaid slide 167 and its operating cam 169.

Because of the fact that the actuating rolls 50 153 are geared to the racks 157 and in frictional contact with the inking rolls 150, 151, and 152, and because the inking roll 152 is in frictional engagement with the transfer roll 159 which in turn is in surface contact with the distributing 55 roll 161 when the frame 147 is in its retracted position, this entire train of rolls is in geared connection with said racks 157 when the frame 147 is near the terminus of its rearward movement. Unless provision is made to release said 60 train of rolls from the restraining effect of its geared connection with the racks 157, it is quite obvious that the operation of the distributing roll 161 by its actuating mechanism will be opposed when the frame 147 reaches a position in 65 which the transfer roll 159 engages the inking roll 152, and that injury to the mechanism or disturbance of its operation may result. To avoid this possibility the inking roll 152 is journaled in bearing members 174 pivoted at 175 upon the 70 side members of the frame 147 and carrying rollers 176 which throughout the major portion of the movements of said frame 147 and its associated elements are arranged in rolling engagement with members 177 suitably fixed in place 75

and extending lengthwise of the racks 157 as illustrated in Figs. 3 and 13. The bearing members 174 are acted on by springs 178 tending to force said rollers 176 in an upward direction. As shown in Figs. 3 and 13 the members 177 are formed with recesses 179 located in registry with the paths of travel of the rollers 176 and adapted to receive said rollers when the frame 147 reaches the end of its return movement. When the rollers 176 pass into said recesses 179 the bearing members 174 will be pivotally actuated by the springs 178 in a direction to shift the inking roll 152 out of surface contact with the one actuating roll 153 so that at this stage the inking roll 152, the transfer roll 159 and the distributing roll 161 are no longer in geared connection with the racks 157 and accordingly are free to rotate independently of the rolls 150, 151, and 153. As soon as the rollers 176 pass out of the recesses 179 when the frame 147 begins an operative movement, the bearing members 174 will be pivotally operated against the tension of the springs 178 to return the inking roll 152 into surface engagement with the one actuating roll 153 and to restore it as part of the train of rolls in geared connection with the racks 157; it will be understood that when this occurs the inking roll 152 has been carried out of engagement with the transfer roll 159 by the forward movement of the frame 147 on the guide rails 149.

The reciprocation of the frame 147 on the rails 149 in proper operative synchronism with the other elements of the machine may be accomplished by means of any suitable mechanism an example of which is shown in the drawings. In its illustrated form this mechanism comprises racks 180 slidably mounted in guides 181 supported at opposite sides of the machine on pins 182 secured to the respective side members 15 as illustrated in Fig. 4. The racks 180 are connected with the side members of the frame 147 by releasable couplings or links 183 pivoted at 184 on said side members of the frame 147, as shown in Fig. 3. The racks 180 furthermore mesh with toothed segments 185 fixed upon a shaft journaled in the side members 15 and carrying a lug 187 which is pivotally connected at 188 with an operating member 189 slotted at 190 for slidable mounting on the shaft 58; the member 189 is provided with a roller 191 projecting into the cam groove 192 of the previously mentioned cam disk 85 located on the shaft 58 as illustrated in Figs. 3 and 4.

The machine as a whole may be operated by any conventional form of driving mechanism as exemplified by the belt 193 and pulley 194, the latter being fixed upon a drive shaft 195 rotatably mounted on the side member 15. The shaft 195 carries a pinion 196 in mesh with a gear 197 fixed upon a countershaft 198 journaled in the side members 15 and provided with a pinion 199 arranged in mesh with the gears 200 and 201 secured respectively upon the shafts 39 and 58 as indicated diagrammatically in Fig. 3.

The novel machine constitutes a so-called "personal-print machine" and is designed primarily to give a personal note to printed advertising or other matter, for instance, by printing the names of individuals for whom such advertising matter is intended in spaces left for this purpose, this personal printed matter being added in such a manner as to give the impression that it was originally included as part of the subject matter 75 with which said personal printed matter is com-

bined. It will of course be understood that other individual items may be correspondingly introduced by printing with the novel machine to otherwise personalize printed matter or to give it some other predetermined individual characteristic. For the purpose of simplifying the explanation and without in any sense intending thereby to limit the scope of the novel machine, it will be assumed that the slugs 59 are provided with lines of type representing the names of selected individuals. As different names require a greater or lesser number of characters, these lines of type will be of different lengths as indicated respectively at *a* and *b* in Figs. 8, 9, and 10; such type also projects above the main portions of 15 the slugs 59 to constitute raised impression producing projections of different lengths on the upper surfaces of said slugs as is also shown in the aforesaid three figures. A supply of such slugs 59 is contained in the chute 86 with the 20 rearmost terminal slug 59 in engagement with the advancing member 110 as shown in Fig. 4. By operating the crank handle 116 or its equivalent, the advancing member 110 may be pivotally actuated to remove the pawl 120 from engagement with the rack 118 to thereby permit the support 111 and with it the advancing member 110 to be adjusted lengthwise of the rack 118 to properly engage the advancing member 110 with the rearmost terminal slug regardless of the 30 number of slugs 59 contained in the chute 86 within the capacity thereof.

In Fig. 3 the machine is illustrated in a position subsequent to the printing of the name or its equivalent carried by the slug 59 which is in position on the lower carrier 46 and just prior to the release of said slug 59 to permit its removal from said carrier 46 and its replacement by the next succeeding slug 59 in the chute 86. As the machine is operated from this point the shafts 40 38 and 58 with the elements carried thereby will be rotated in operative synchronism to cause the roller 55 of the rocking lever 49 to enter the portion *d* of the cam groove 56 which acts on said roller 55 to swing the lever 49 in a direction to 45 move the lower carrier 46 downwardly to a slight extent from the position shown in Fig. 3. As these operations occur, the rod 69 which rests upon the base plate 16 will remain stationary and at its upper end will act upon the cam 67 50 to pivotally actuate the member 62 against the tension of the spring 65 and to thereby move the clamping member 61 in a direction away from the slug 59 on the carrier 46 to the releasing position illustrated in Fig. 7. Coincidentally with these 55 operations the cam 106 will be correspondingly rotated and by means of its cam groove 197 in cooperation with the roller 108 will oscillate the lever 99 upwardly in Fig. 4 to adjust the transfer member 90 and the parts carried thereby lengthwise of the guide member 88 and guide wall 89 to a point beyond the chute 86. At the proper moment the cam projection 130 on the cam 106 by engagement with the roller 131 will slidably actuate the operating member 127 to correspondingly operate the rack 118 and with it the support 111 in a manner to cause the advancing member 110 to shift the supply of slugs 59 in the chute 86 toward the left in Fig. 4 into engagement with the upright guide wall 89 of the guide member 70 88. The portion *d* of the cam groove 56 is designed to maintain the clamping member 61 in the releasing position shown in Fig. 7 for a length of time sufficient to permit the slug 59 located on the lower carrier 46 and which previously has per- 75

formed its printing function to be removed from said carrier 46 and to be replaced by the next successive slug 59 from the chute 86. This removal and replacement of slugs is accomplished by the cam groove 107 of the cam 106 in co-operation with the roller 108 whereby the lever 99 is oscillated at its pivot 100 in a direction to shift the transfer member 90 lengthwise of the guide member 88 and guide wall 89 toward the chute 86; during the first stages of this movement the propelling members 92 and 93 occupy the positions on the transfer member 90 illustrated in Fig. 8. As the above-mentioned shifting movement of the transfer member 90 toward the chute 86 continues, the propelling member 93 will pass over the forward terminal slug 59 and finally will engage the line of type either *a* or *b* or their equivalent on the particular slug 59 which happens to be the forward terminal slug in said chute 86 at the time. As the propelling member 93 engages the line of type, the continuing movement of the transfer member 90 will cause the propelling member 93 to be pushed backwardly into the transfer member 90 and through the medium of its rack 94 to rotate the pinion 95 to thereby cause the lower propelling member 92 by means of its rack 94 to be moved out of the transfer member 90. These relative adjustments of the propelling members 93 and 92 continue until the member 92 engages the body of the forward terminal slug 59 which lies in the chute 86 in the path of the transferring means. At this stage therefore the upper propelling member 93 will be in engagement with the line of type *a* or *b* while the lower propelling member 92 will be in contact with the body of the slug 59; as illustrated in Figs. 9 and 10 the length of the lines of type *a* and *b* will determine the adjustment of the propelling members 93 and 92, said adjustment being predetermined by the length of the line of type *a* or *b* or their equivalent and the location thereof on the slug 59, and being such as to always shift the slugs 59 to a position on the lower carrier 46 in which the line of type *a*, *b* or their equivalent will occupy the proper printing position regardless of any variations in the length of such lines of type on different slugs. As the movement of the transfer member continues the forward terminal slug 59 in the chute 86 will be shifted from the latter toward the delivery end of the guide member 88 and finally will engage the slug 59 which is located upon the lower carrier 46. A continued movement of the transfer member 90 will cause the succeeding slug 59 to shift the preceding slug 59 from the lower carrier 46 into the disposal chute 134 from which it passes into the trough 135. As this removal of the preceding slug 59 from the lower carrier 46 takes place, the next succeeding slug 59 will at the same time be shifted into printing position on said lower carrier 46 between the plate or stop 60 and the clamping member 61 which at this stage is still in its inoperative or releasing position as shown in Fig. 7. When this replacement of the slugs has taken place on the lower carrier 46, the roller 55 will pass out of the portion *d* of the cam groove 56 and the latter in co-operation with said roller 55 will pivotally actuate the rocking lever 49 in a direction to begin the upward movement of said lower carrier 46. Because of the fact that the rod 69 does not partake of this upward movement of the carrier 46 but remains in engagement with the base plate 16 by gravity, the upper end of said rod 69 will release the cam 67 and accordingly permit

the spring 65 to adjust the clamping member 61 into engagement with the slug 59 which is now on said carrier and thereby clamp said slug against the plate or stop 60 to secure it in printing position upon said lower carrier 46. During the 5 major portion of these operations the roller 33 has remained in the concentric portion of the cam groove 34 so that the rocking lever 30 and its associated elements have remained substantially stationary or at least have not been actuated to any appreciable degree. Previous to these operations or at any appropriate period thereof, the sheet of paper or equivalent material on which the printing is to be done by the particular slug 59 located on the lower carrier 46, has been 15 placed in proper position upon the bed plate 17 with the space in which the name of said slug is to be printed in registry with the opening 45 therein.

During the time that the above operations are 20 taking place, the cam groove 192 by acting on the roller 191 will through the medium of the operating member 189 rock the shaft 186 to swing the segments 185 in a direction to cause the racks 180 to gradually shift the frame 147 lengthwise of the guide rails 149 toward the left in Fig. 3. During this travel of the frame 147, the inking rolls 150, 151 and 152 to which ink has been transferred from the transfer roll 159, will be rotated about their axes through the 25 medium of the pinions 156 and rack 157; in the movement of the frame 147 lengthwise of the guide rails 149 in the manner described the inking rolls 150, 151, and 152 will pass over and in surface contact with the inking platen 171 30 so that the surfaces of said rolls 150, 151, and 152 will become evenly coated with printing ink. The operations are so timed that the inking rolls 150, 151, and 152 will successively pass over and in contact with the line of type located on the 35 slug 59 which is fixed upon the lower carrier 46 at the time, to apply a coating of ink to said line of type for printing purposes; the frame 147 and the elements carried thereby will be shifted in a return direction to a sufficient degree to move 40 the inking rolls 150, 151, and 152 backward beyond the vertical path of the carrier 46 before upward movement of the latter has commenced. After the inking of the slug on the carrier 46 has been finished, the rocking levers 30 and 49 45 will be rocked on their pivots in inverse relation by the cam grooves 34 and 56 in co-operation with the respective rollers 33 and 55. As a result the upper carrier 21 will be moved downwardly to correspondingly move the pressure member 55 50 22, while the lower carrier 46 with the slug 59 which is to make the impression carried thereby will simultaneously be adjusted in an upward direction. The arrangement is such that the stamping or pressure member 22 will engage the 55 upper surface of the paper or other material which is to receive the impression at approximately the same moment that the line of type on the slug 59 located on the carrier 46 engages the lower surface of said sheet at the point at 60 which the impression is to be made. It will be understood that the upper carrier 21 has previously been adjusted by means of the adjusting screw 25 or its equivalent to set the stamping or pressure member 22 in a position for co-operation with the printing slug 59 to produce an efficient and satisfactory impression therefrom. As the lower carrier 46 is moved upwardly the shoulder 72 of the arms 70 will be forced beneath the lower end of said carrier 46 by the action 70 75

of the spring 74 so that said shoulder 72 serves to support the lower carrier 46 from below while the slug 59 is making its impression, whereby the operating mechanism is relieved from excess strains during the actual printing operations. If for any reason it should become necessary to temporarily adjust the pressure developed by the stamping or pressure member 22 in opposition to the printing pressure developed by the printing 10 slug 59, this adjustment may be accomplished at will by swinging the operating lever 41 on its pivot 42 to rotatably adjust the shaft 33 and eccentric 39 carried thereby and to thus temporarily change the location of the pivot 31 on 15 which the lever 30 is arranged to swing. When the printing slug 59 has made its impression on the paper or equivalent material located on the bed plate 17, the pin 84 will have engaged the tripping pawl 82 which accordingly will be swung 20 on its pivot 81 in a direction to develop a pull upon the link 77 effective upon the lug 75 to swing the arm 10 toward the left in Fig. 3 and to thus remove its shoulder 72 from beneath the lower carrier 76. Continued operation of the mechanism 25 will rock the levers 30 and 49 in inverse relation in return directions so that the upper carrier 21 will be moved upwardly while the lower carrier 46 at the same time will be moved downwardly back to the positions shown in Fig. 3, 30 whereupon the cycle of operations described will be repeated. As the shaft 58 is rotated during the cycle of operations set forth above, the disk 146 will rotate therewith and will reciprocate the pushing member 137 at periodic intervals in a 35 manner to advance the slugs accumulated in the trough 135 in successive steps lengthwise thereof; the operative movements of the pushing member 137 to shift the accumulated slugs 59 in the trough 135 are so timed that the end portion of 40 the trough 135 located in registry with the chute 134 will always be free to receive the slugs 59 as they are successively transferred from the lower carrier 46.

The machine is extremely simple in construction and needs no particularly skilled supervision in its operation as will be apparent; all that is required on the part of the operator is to place a supply of slugs 59 from which impressions are to be made, in the chute 86 and to place successive sheets of paper or other material in proper position on the bed plate 17 to receive said impressions in the predetermined places. With the novel machine it is possible to impress or print names or other items in 50 relation with previously printed matter on said sheets or the like to impart thereto a personal touch and to give the impression that each sheet or its equivalent has been independently printed or created in its entirety for a given individual or for any other given purpose. The feeding of the slugs 59 to the printing mechanism, the positioning thereof in proper printing position regardless of variations in the dimensions of the items to be printed and the removal of said slugs 55 from the printing mechanism are all accomplished automatically and without any manual effort on the part of the operator.

It is to be understood that the matter to which the individual items, as exemplified by the names of individuals, are added by the novel machine, may be produced by any suitable printing operation such as printing from type or lithographing, etc.

Various changes in the specific forms shown 75 and described may be made within the scope of

the claims without departing from the spirit of the invention.

We claim:

1. A printing machine for adding printed items to previously printed matter comprising a support for a plurality of slugs each provided with type constituting the item to be added to said previously printed matter, printing mechanism having a linearly movable printing member normally in receiving relation to said support, means for shifting said slugs successively to a position on said support for delivery to said printing member, means for intermittently transferring said slugs in sequence from said support to said printing member for movement therewith and for removing each next previous slug therefrom, and mechanism for operating said printing mechanism in the intervals between the transferring and removal of successive slugs to and from said printing member. 20

2. A printing machine for adding printed items to previously printed matter comprising a support for a plurality of slugs each provided with type constituting the item to be additionally printed thereby, printing mechanism, means for feeding said slugs in sequence to said printing mechanism and for removing each next previous slug therefrom, and adjustable means forming part of said feeding means adapted to automatically compensate for different lengths in the 25 lines of type on individual slugs whereby the latter are automatically shifted to proper printing position regardless of variations in the lengths of said lines of type. 30

3. A printing machine for adding printed items to previously printed matter comprising a bed plate for supporting the printed sheets to which printed items are to be added, and provided with an opening, upper and lower carriers located in vertical registry with each other and with said opening, a chute for containing a supply of slugs each provided with type constituting the item to be added to said previously printed matter, means for shifting said slugs in succession from said chute to said lower carrier for movement therewith and for removing each next preceding slug therefrom, mechanism for operating said carriers in inverse relation to impress the items on said slugs on said sheets, and movable clamping means on said lower carrier for clamping successive slugs thereon and for releasing the same, said clamping means being automatically controlled by the operative movements of said lower carrier. 45 50

4. A printing machine for adding printed items to previously printed matter comprising a bed plate for supporting the printed sheets to which printed items are to be added, and provided with an opening, upper and lower carriers located in vertical registry with each other and with said opening, a chute for containing a supply of slugs each provided with type constituting the item to be additionally printed thereby, means for shifting said slugs in succession from said chute to said lower carrier and for removing each next preceding slug therefrom, clamping means for releasably clamping the slugs on said lower carrier, means automatically controlled by the operative movements of said lower carrier for operating said clamping means in timed relation with said shifting means to permit the replacement of slugs on said lower carrier and their removal therefrom in individual succession, and mechanism for operating said carriers in inverse relation with the shifting of the slugs. 60 65 70 75

tion to impress the items on said slugs on said sheets.

5. A printing machine for adding printed items to previously printed matter comprising a bed plate for supporting the printed sheets to which printed items are to be added, and provided with an opening, upper and lower carriers located in vertical registry with each other and with said opening, a chute for containing a supply of slugs 10 each provided with type constituting the item to be additionally printed thereby, means for shifting said slugs in succession from said chute to said lower carrier and for removing each next preceding slug therefrom, adjustable means 15 forming part of said shifting means adapted to compensate for different lengths in the lines of type on individual slugs whereby the latter are automatically shifted to proper printing position on said lower carrier regardless of variations 20 in the lengths of said lines of type, and mechanism for operating said carriers in inverse relation to impress the items on said slugs on said sheets.

6. A printing machine comprising a bed plate 25 for supporting the material for receiving printed impressions and provided with an opening, upper and lower carriers located in vertical registry with each other and with said opening, a pressure member movable with said upper carrier, a rocking 30 lever on which said upper carrier is mounted, a second rocking lever on which said lower carrier is mounted, a chute for containing a supply of printing slugs, means for shifting said slugs from said chute to said lower carrier and for removing the next preceding slug therefrom in predetermined succession, clamping means for releasably clamping the slugs on said lower carrier, means automatically controlled by the operative 35 movements of said lower carrier for operating said clamping means in timed relation with said shifting means to permit the replacement of slugs thereon and their removal therefrom in individual succession, and mechanism for rocking said levers to operate said carriers in inverse relation 40 for causing said slugs to produce printed impressions on said material.

7. A printing machine comprising a support for a plurality of printing slugs each containing at least one line of type constituting the matter to be printed thereby, printing mechanism for causing said slugs to produce printed impressions, a movable transfer member for shifting said slugs from said support to said printing mechanism and for removing them from the latter in succession, and propelling members movably carried by said transfer member and automatically adjustable by engagement with successive slugs to compensate for variations in the length of the lines of type carried thereby whereby said slugs are automatically shifted to proper printing position 50 regardless of said variations.

8. A printing machine comprising a support for a plurality of printing slugs each containing at least one line of type constituting the matter to be printed thereby, printing mechanism for causing said slugs to produce printed impressions, a movable transfer member for shifting said slugs from said support to said printing mechanism and for removing them from the latter in succession, and parallel propelling members slidably movable in inverse relation relatively to said transfer member, one of said propelling members engaging the lines of type on said slugs to adjust both propelling members in a manner to compensate for variations in the length of the lines of 60

type carried by different slugs whereby said slugs are automatically shifted to proper printing position regardless of said variations.

9. A printing machine comprising a chute for a plurality of printing slugs each containing at least one line of type constituting the matter to be printed thereby, printing mechanism for causing said slugs to produce printed impressions, transfer means for shifting said slugs from said chute to said printing mechanism and for removing them from the latter in succession, said transfer means being automatically adjustable by contact with the slugs to compensate for variations in the lengths of the lines of type carried thereby whereby said slugs are automatically shifted to proper printing position regardless of said variations, and means for advancing the slugs in said chute into operative relation with said transfer means.

10. A printing machine for adding printed items to previously printed matter comprising a support for a plurality of slugs each provided with type constituting the item to be added to said previously printed matter, printing mechanism including a movable printing member, 25 means for feeding said slugs in sequence to a printing position on said printing member for movement therewith and for removing each next previous slug therefrom, means for shifting said slugs relatively to said support into operative relation with said feeding means, a trough for receiving the slugs discarded from the printing member, and means independent of said slug feeding and shifting means for progressively moving said slugs lengthwise of said trough for 30 final disposition.

11. A printing machine comprising a support for a plurality of printing slugs, vertically movable upper and lower carriers located in vertical registry with each other, means for shifting said 40 slugs in succession from said support to a printing position on said lower carrier for movement therewith, mechanism for operating said carriers in inverse vertical relation to cause said slugs to produce printed impressions, a device for supporting said lower carrier to prevent depression thereof during each printing stage, and means for adjusting said device to release said lower carrier at the end of each printing stage.

12. A printing machine comprising a support 50 for a plurality of printing slugs, vertically movable upper and lower carriers located in vertical registry with each other, means for shifting said slugs in succession from said support to a printing position on said lower carrier, a clamping member movably mounted on said lower carrier for releasably clamping successive slugs thereon, a cam fixed on said clamping member, and a rod movably mounted on said lower carrier and cooperating with said cam to automatically control 55 said clamping member, said lower carrier during a portion of its downward movements moving relatively to said rod whereby the latter acts on said cam to adjust said clamping member to an inoperative position to release a given slug for removal from said lower carrier.

13. A printing machine comprising a support for a plurality of printing slugs, vertically movable upper and lower carriers located in vertical registry with each other, a pressure member movable with said upper carrier, means for shifting said slugs in succession from said support to a printing position on said lower carrier for movement therewith, upper and lower pivoted levers on which said carriers are respectively mounted, 70

means for rocking said levers to operate said carriers vertically in inverse relation to cause said slugs to produce printed impressions, and manually controlled means for adjusting the pivot of the upper lever at will to thereby vary the effective pressure developed by said pressure member.

14. A printing machine comprising a support for a plurality of printing slugs, vertically movable upper and lower carriers located in vertical registry with each other, said lower carrier being movable downwardly to a lowered inking position, ink distributing means, a horizontally movable support, a plurality of inking rolls carried thereby, means for horizontally reciprocating said support to bring one of said inking rolls into ink receiving relation with said distributing means and for passing said inking rolls over and in contact with the slug on said lower carrier in the lowered inking position thereof to ink said slug, and means on said movable support for distributing ink to all of the inking rolls thereon as said support travels toward said lower carrier.

15. In a printing machine, the combination of vertically movable upper and lower carriers located in vertical registry with each other, and constituting means for printing impressions from slugs carried by said lower carrier, the latter being movable to an inking position, ink distributing means, stationary guide rails, a support movable lengthwise of said rails, a plurality of inking rolls carried by said support, actuating rolls on said support in surface contact with said inking rolls and forming therewith a train of rolls, stationary racks located in parallel relation to said guide rails, pinions movable with said actuating rolls and meshing with said racks whereby said train of rolls is normally geared to said racks, means for reciprocating said support lengthwise of said rails to bring one of said inking rolls into ink receiving relation with said ink distributing means and for passing said inking rolls over and in contact with the slug on the lower carrier in the inking position thereof to ink said slug, and means whereby the geared connection of said train of rolls with said racks is broken when said one inking roll is in ink receiving relation with said ink distributing means.

16. A printing machine for adding printed items to previously printed matter comprising a support for a plurality of slugs each provided with type constituting the item to be added to said previously printed matter, printing mechanism including a printing member normally in receiving relation to said support, means for shifting said slugs successively to a position on said support for delivery to said printing member, means for intermittently transferring said slugs in sequence from said support to said printing member and for removing each previous slug therefrom, operating means for said printing mechanism whereby said printing member is moved to and from printing position, and movable clamping means for clamping the slug in individual succession on said printing member and for releasing said slugs, said clamping means being automatically controlled by the operative movements of said printing member.

17. A printing machine for adding printed items to previously printed matter comprising a support for a plurality of slugs each provided with type constituting the item to be added to said pre-

viously printed matter, said support having a delivery end to which said slugs are brought in succession, a disposal chute having its receiving end in spaced registry with the delivery end of said support and at a corresponding level therewith, printing mechanism including a printing member movable in the space between the delivery end of said support and the receiving end of said disposal chute and adapted to occupy a position of rest between said delivery and receiving ends at a corresponding level therewith whereby said delivery end of the support, said printing member and said receiving end of the disposal chute together constitute a substantially continuous path, and means for transferring a terminal slug from the delivery end of said support to said printing member for movement therewith and thereby forcing the last previous slug from said printing member into the receiving end of said disposal chute between successive operations of said printing mechanism.

18. A printing machine for adding printed items to previously printed matter comprising a support for a plurality of slugs each provided with type constituting the item to be added to said previously printed matter, printing mechanism including a printing member normally in receiving relation to said support, means for shifting said slugs successively to a position on said support for delivery to said printing member, means for intermittently transferring said slugs in sequence from said support to said printing member and for removing each previous slug therefrom, operating means for said printing mechanism whereby said printing member is moved to and from printing position, and a spring controlled clamping member for releasably clamping the slugs in individual succession on said printing member.

19. A printing machine for adding printed items to previously printed matter to accord therewith comprising a support for a plurality of slugs each provided with type constituting the item to be added to said previously printed matter, printing mechanism including a movable printing member normally in receiving relation to said support, means for intermittently transferring successive slugs bodily from said support to said printing member for movement therewith, and means for operating said printing member in the intervals between said intermittent transfer of slugs to cause the slug carried by said printing member to make an impression.

20. A printing machine for adding printed items to previously printed matter to accord therewith comprising a support for a plurality of slugs each provided with type constituting the item to be added to said previously printed matter, printing mechanism including a movable printing member normally in receiving relation to said support, means for intermittently transferring successive slugs bodily from said support to said printing member for movement therewith, a spring controlled clamping member for releasably clamping successive slugs on said printing member, and means for operating said printing member in the intervals between said intermittent transfer of slugs to cause the slug carried by said printing member to make an impression.

HARRY L. LATZ.

STEPHEN H. PLUM, 2p.
